UNITED STATES PATENT OFFICE.

HUGH SANGSTER, OF PLANO, ILLINOIS, ASSIGNOR OF ONE-HALF OF HIS
RIGHT TO THOMAS J. BEEBE, OF SAME PLACE.

INCASED CAN.

SPECIFICATION forming part of Letters Patent No. 232,905, dated October 5, 1880.

Application filed March 20, 1880. (No model.)

To all whom it may concern:

Be it known that I, HUGH SANGSTER, a citizen of the United States, residing in Plano, in the county of Kendall and State of Illinois, 5 have invented certain new and useful Improvements in Incased Cans, of which the following is a specification.

My invention relates to the construction of cans for holding liquids and other materials, 10 and has for its objects to connect the hoops, secure the can in an outer holder or casing, facilitate the insertion and removal of the can from its holder, secure the bail, strengthen the bottom, and retain the casing and can in 15 connection.

In the accompanying drawings, Figure 1 represents a side elevation of the case or removable jacket complete; Fig. 2, a side elevation of the sheet-metal can belonging to it. 20 Fig. 3 is a top view of the can and jacket combined, and Fig. 4 is a top view of the jacket separate from the can. Fig. 5 represents a horizontal section in line Y, Fig. 7, through a portion of the jacket, and the sheet-metal strip for 25 holding the ends of the jacket in place and for reeving the handle. Fig. 6 is a portion from the upper part of the jacket, showing an enlarged side elevation of the bail and the fastening device in position for allowing the sheet- 30 metal can to be started upward preparatory to being taken out, and one of the ears upon which the bail swings. Fig. 7 is a vertical section through the jacket and can in line V, Fig. 3, and through the sheet-metal strip for 35 holding the jacket ends in place in line X, Fig. 5. Fig. 8 is an enlarged portion from the upper part of the jacketed can, showing a top view of part of the bail, one of the ears, and a fastening device in position for holding the top of the 40 can down. Fig. 9 represents an enlarged fragment of the can-bottom. Fig. 10 is a top view of an enlarged portion of a jacket or case, showing a similar view of the fastening device in position for allowing the can to be released 45 from the jacket, and Fig. 11 is a section through a portion of a can-jacket and hoop, showing a modified way of holding the top of the can down to the jacket.

Heretofore one of the greatest objections to

an incased metallic can has been the difficulty 50 of getting at the metal can to repair it in case of a leakage without in some way injuring the holder case or jacket. For this reason one of the objects of my invention is to make the can easily removable from the jacket when required without the necessity of injuring the can-jacket by drawing nails or screws therefrom or in any way separating any of the parts of the jacket.

B represents a can, and A represents the 60 jacket; A', the hoops, which are strips of wood bound with sheet metal, as shown in Figs. 7 and 11; but the ordinary hoops, either of metal or of wood, may be used.

The jacket may be formed so that the grain 65 of the wood may run either horizontally around it—*i. e.*, lengthwise of the slip—or vertically, as may be desired; but the strongest way I believe is to have the grain run lengthwise of the strip forming the jacket. The sheet from 70 which the jacket is to be made, after being wet in water for fifteen or twenty minutes, is formed partly up in a small pair of tinman's rollers and then left over night, after which it is again put through the rollers and formed to 75 a complete circle, and may be passed through bright rollers to be polished, if desired. The two ends forming the seam are united by being slipped into a metallic seaming-piece, H', as shown in Fig. 5. A handle, G, may be soldered or otherwise fastened to the piece H', if desired; but the handle is not a necessary part of this invention, and will form the subject of another application. The hoops A' are connected by two or three or more metallic 80 strips, D, extending vertically from one hoop to the other and soldered at the ends to the hoops, or otherwise secured. The jacket is now ready for the ears, which are in the form of rivets having the heads inside. They are 85 passed through the metallic strips D, and through the jacket, as shown in Fig. 4, and are then soldered to said strips. The bail E is secured at each end and nearly at right angles to an arm, F, terminating in a lip, F', 90 which arm is hung to one of the ears, and a washer, J, for completing the ear, is now put on and either riveted or soldered. (See Figs.

4, 6, 8, and 10.) When the bail is moved down the lip F' will spring over the top of the can, as shown in Fig. 8. The end of the lip is so curved that if the bail be now lifted the lip 5 will be forced outward, as shown in Fig. 10, in which position the sheet-metal can may be raised partly out of the jacket. The bail may be now turned down and the can withdrawn.

10 If desired, the arms F on the bail may be dispensed with, and a thin strip of metal, C² in Fig. 11, may be slipped up between the hoop and the can, and the lower end bent outward over the lower edge of the top hoop, 15 and the upper end bent inward over the top of the can, as shown in this case.

When it is desired to take the can out of the jacket, all that is necessary to do is to bend the upper end vertically, and the can can be 20 easily removed.

E' represents a semicircular piece of sheet metal, to be used when greater strength is required, and only then, for instance, on large cans.

25 H is a short metallic plate, which is soldered or otherwise secured to the top hoop of the

case. It is formed with a projection or cross-rib, j, over which the bail E may be sprung.

I do not here claim the construction of can shown, as it will form the subject of a separate application for Letters Patent.

I claim—

1. The combination, in a holder or case for a sheet-metal can, of jacket A, upper and lower hoops, A', and series of vertical strips D, 35 whereby the hoops are confined to the case, substantially as described.

2. The hoops A', consisting of wood and a covering of sheet metal, combined with the jacket and strips D, as specified. 40

3. The combination, with the case, of a bail, E, provided with arms F, which terminate in lips F', the latter being arranged to be forced over the top edge of the case, as set forth.

4. The combination, with the case and bail, 45 of the plate H, having a cross-rib, j, over which the bail may be sprung, substantially as set forth.

HUGH SANGSTER.
